UNITED STATES PATENT OFFICE.

ARCHIBALD F. REDDIE, OF PHILADELPHIA, PENNSYLVANIA, ASSIGNOR TO
McCALLUM & McCALLUM, OF SAME PLACE.

DESIGN FOR CARPET.

SPECIFICATION forming part of Design No. 25,296, dated **March 24, 1896.**

Application filed February 24, 1896. Serial No. 580,529. Term of patent 31 years.

To all whom it may concern:

Be it known that I, ARCHIBALD F. REDDIE, a citizen of the United States, residing at the city of Philadelphia, in the county of Philadelphia and State of Pennsylvania, have invented and produced a new and original Design for a Carpet or other Fabric, of which the following, taken in connection with the accompanying drawing, is a specification.

10 The pattern or ornamentation illustrated in the accompanying drawing embodies my invention and produces that distinguishing appearance which characterizes articles to which it is applied and differentiates them from others of like class.

In the drawing, A is the body, B the border, and A and B the complete carpet.

My design may find expression in an endless variety of colors and combinations of colors, and may of course be made to appear upon the surface of Brussels, Wilton, velvet and other carpets.

The leading or characteristic feature of my design may be said to be the floral ornaments or conventionalized representations of the carnation flower *a b c*, arranged lineally, or substantially so, and interspersed between representations of wandering foliage *d*.

What I claim as new, and desire to secure by Letters Patent, is—

1. In the design for a carpet the body A, substantially as shown.
2. In a design for a carpet the border B, substantially as shown.
3. The design for a carpet consisting of the body A, and the border B, substantially as shown.

In testimony whereof I have hereunto signed my name in the presence of two witnesses.

ARCHIBALD F. REDDIE.
